UNITED STATES PATENT OFFICE.

NIIS M. ROSENDAHL, OF CHICAGO, ILLINOIS, ASSIGNOR TO FREDERICK C. AUSTIN, OF CHICAGO, ILLINOIS.

LIQUID-METERING TANK.

1,210,988.

Specification of Letters Patent. Patented Jan. 2, 1917.

Application filed November 6, 1911. Serial No. 658,862.

To all whom it may concern:

Be it known that I, Nils M. Rosendahl, a citizen of the United States of America, and resident of Chicago, Cook county, Illinois, have invented a certain new and useful Improvement in Liquid-Metering Tanks, of which the following is a specification.

My invention relates to water tanks or reservoirs for use in connection with concrete mixers, or for use in other places where water is employed for mixing or flushing purposes, and where the conditions are such that the water must be measured off to give the desired quantity each time, whereby the mixing or flushing operation will always be characterized by the right amount of water.

The object of my invention is to provide novel and improved means whereby any portion of the water in the tank or reservoir may be measured off to give the desired quantity for mixing or flushing purposes.

It is also an object to provide an improved construction and arrangement whereby a siphon may be easily adjusted to vary the quantity of water to be drawn off from the tank or reservoir.

To these and other useful ends, my invention consists in matters hereinafter set forth and claimed.

In the accompanying drawings, Figure 1 is a side elevation of a tank or reservoir embodying the principles of my invention, showing the same connected with the hopper of a concrete mixer. Fig. 2 is an enlarged sectional view of the valve employed for controlling the admission and withdrawal of water to and from the tank. Fig. 3 is an enlarged partial longitudinal section of the said tank, showing the adjustable siphon mechanism for regulating the withdrawal of the water. Fig. 4 is a transverse section on line 4—4 in Fig. 3. Fig. 5 is a transverse section on line 5—5 in Fig. 3.

As thus illustrated, my invention comprises a cylindric tank or reservoir A provided at one end with a depressed or countersunk head a, and at the other end with a convex or bulging head a'. Upon the inner surface of the center of the head a the casting B is secured by rivets b, said casting having a stuffing box portion b' that projects through the head a to receive the

threaded cap or nut b². This casting B has a cylindric chamber b³ with reduced end portions b⁴ and b⁵, which end portions receive and fit the annular flanges b⁶ and b⁷ on the horizontal end of the siphon pipe b⁸. This pipe has the downwardly bent end portion b⁹, and the lateral openings b¹⁰ at its upper end, which openings communicate with the chamber b³. A vertical pipe b¹¹ enters the bottom of the tank and is screwed into the bottom of the casting B, whereby the pipes b⁹ and b¹¹ are always in communication with each other through the medium of the chamber b³. The effect is a siphon of which the pipe b⁸ is the shorter leg and the pipe b¹¹ the longer leg. A stem b¹² is secured to the upper end of the pipe b⁸ and extends outward through the stuffing box b'—b², a spring b¹³ and a handle b¹⁴ being applied to the outer end of said stem, said spring serving to hold the pipe in position. With this arrangement, the pipe b⁸ can be swung around or revolved to any position, as shown in dotted lines in Figs. 3 and 4. When in the position shown in full lines in Fig. 3, nearly the entire contents of the tank can be siphoned off. But with the siphon pipe b⁸ in a more or less elevated position, a lesser portion of the contents will be drawn off. Thus the horizontal portion of the pipe b⁸ rotates in the casting B to vary the amount of water drawn off.

Any suitable arrangement can be employed for connecting the tank with the hopper C of a concrete mixer. As shown, the pipe b¹¹ is connected with the top of the three way valve D, which latter has a water supply pipe d and a discharge pipe d', which latter leads to the said hopper through a flexible pipe c, whereby the mixer may tilt back and forth in the usual and well known manner. When the valve D is adjusted as shown in full lines in Fig. 2, then the supply pipe d is cut off and the contents of the tank are drawn off through the pipe d', to the extent permitted by the adjustment of the siphon. But when the valve is in the position shown in dotted lines in Fig. 2, then the water from the supply pipe d enters the tank, and the pipe d' is cut off, whereby the tank may fill.

A siphon discharge tank or reservoir of

this character may be employed for various purposes. The adjustment for varying quantities is easily accomplished by simple and reliable means. Thus any portion of 5 the contents may be drawn off at will.

It will be seen that the discharge pipe d' has a siphon head in the tank, this head comprising a fixed pipe b^{11} , the swivel bearing B and the swiveled pipe b^9 , as previously described. The swiveled section b^9 is, it will be seen, adjustable without disturbing the offtake d' , and without disturbing 10 the valve D by which the discharge is controlled, and by which the filling of the 15 tank is also controlled. The siphon head constitutes both the inlet and the outlet for the tank, as it is used for filling the tank as well as for discharging the contents therefrom.

With the foregoing construction, the pipes 20 b^9 and b^{11} and the swivel head B form a siphon, both legs of which are inside of the tank, the pipe b^{11} (which leads downward from the swivel head and passes 25 through the bottom of the tank) forming the long leg of the siphon, and the swiveled or swinging pipe b^9 forming the short leg of the siphon. Furthermore, it will be seen 30 that the siphon thus inclosed entirely within the tank is so constructed and arranged that the pipe b^9 swings about the longitudinal axis of the cylindrical and horizontally disposed tank, so that the end of this 35 pipe is always the same distance from the wall of the tank. The construction does not operate as a siphon, of course, except when the end of the pipe b^9 is some distance below its swiveled end; for when this pipe is 40 in horizontal position, or in the position shown in dotted lines in Fig. 3, there can be no siphoning action.

I do not limit myself to the exact construction shown and described.

What I claim as my invention is:

1. A liquid metering apparatus comprising 45 a tank, a fixed coupling member disposed a distance above the bottom in said tank, a fixed pipe supported by and leading downward from said member, a pipe swiveled in said member and thereby capable of extending either downward or upward or 50 endwise, the two pipes coöperating to form a siphon with a swinging short leg and a fixed long leg for draining off the contents of the tank through the fixed pipe which is longer than the swiveled pipe, and means to 55 adjust the position of said swiveled pipe, said means including an axial stem for said swiveled pipe, a spring on said stem to hold the swiveled pipe in adjusted position, and a handle for said stem, said handle being parallel with said short pipe to indicate the position of the latter, said short pipe having a horizontal section provided with lateral openings, and said member having a 60 chamber communicating with said openings.

2. The combination of a tank, a swivel- 65 head fixed to said tank and operable about

a horizontally disposed axis, a short pipe supported by said head to swing about said axis, a long pipe having its upper end fixed 70 in the under side of said head and extending downward through the bottom of said tank, the two pipes and said swivel-head being inclosed by said tank and forming a siphon with a swinging short leg and a fixed long leg to draw off the contents thereof, a connection for the lower end of said fixed pipe, and an external handle for changing 75 the position of the short pipe to vary the quantity of the discharge.

3. The combination of a tank, a swivel-head fixed to said tank and operable about a horizontally disposed axis, a short pipe supported by said head to swing about said axis, a long pipe having its upper end fixed 80 in the under side of said head and extending downward through the bottom of said tank, the two pipes and said swivel-head being inclosed by said tank and forming a siphon with a swinging short leg and a fixed long leg to draw off the contents thereof, a connection for the lower end of said fixed pipe, and an external handle for changing 85 the position of the short pipe to vary the quantity of the discharge, said connection having means for using said pipes to fill the tank.

4. A liquid metering apparatus comprising 90 a tank, a fixed coupling member disposed a distance above the bottom in said tank, a fixed pipe supported by and leading downward from said member, a pipe swiveled in said member and thereby capable of extending either downward or upward or 95 endwise, the two pipes coöperating to form a siphon with a swinging short leg and a fixed long leg for draining off the contents of the tank through the fixed pipe which is longer than the swiveled pipe, and means to 100 adjust the position of said swiveled pipe, said means including an axial stem for said swiveled pipe, a spring on said stem to hold the swiveled pipe in adjusted position, and a handle for said stem, said handle being parallel with said short pipe to indicate 105 the position of the latter, said short pipe having a horizontal section provided with lateral openings, and said member having a chamber communicating with said openings.

5. The combination of a tank, a swivel-head fixed to said tank and operable about a horizontally disposed axis, a short pipe supported by said head to swing about said axis, a long pipe having its upper end fixed 110 in the under side of said head and extending downward through the bottom of said tank, the two pipes and said swivel-head being inclosed by said tank and forming a siphon 115 with a swinging short leg and a fixed long leg to draw off the contents thereof, a con-

nection for the lower end of said fixed pipe, and an external handle for changing the position of the short pipe to vary the quantity of the discharge, said tank being cylindric and having its axis of curvature coincident with said axis of the swivel-head, so

5 that said short pipe may swing around with its end close to the cylindric wall of said

tank, and means to hold said short pipe in any desired position.

Signed by me at Chicago, Illinois, this 31st day of October, 1911.

10 NILS M. ROSENDAHL.
